EDGING MACHINE

Conrad B. Schafer, Toledo, Ohio, and Edward Oberstar, Ottawa, Ill., assignors to Libbey-Owens-Ford Glass Company, Toledo, Ohio, a corporation of Ohio

Application December 15, 1939, Serial No. 309,432

20 Claims.

(Cl. 51—74)

The present invention relates broadly to surfaceing machines and, more particularly, to a machine for grinding and/or polishing the edges of sheets or plates of glass and the like.

Generally speaking, this invention contemplates the provision of an edging machine having a substantially horizontal runway upon which one or a plurality of sheets or plates of glass or the like are supported on edge in a vertical position and along which are adapted to be moved beneath one or a series of grinding and/or polishing wheels to surface the upper edges of said sheets or plates. Although the invention will be hereinafter specifically described in connection with the grinding operation, it will be understood that it may be used equally well for polishing by simply substituting polishing wheels for the grinding wheels.

It is an aim of this invention to provide an edging machine of the above general character of novel and improved construction and arrangement and which, while primarily designed for the grinding of curved edges of different contour, is also adapted for grinding straight edges or a combination of both.

Another object of the invention is the provision of an edging machine of the above character embodying one or more grinding wheels mounted for free vertical floating movement so that they can freely follow the contour of the upper edges of the glass sheets or plates as the said sheets or plates are passed therebeneath.

Another object of the invention is the provision of an edging machine of the above character having means for varying the pressure exerted by the grinding wheel upon the upper edges of the glass sheets or plates as they reach predetermined positions during the grinding operation whereby to obtain maximum grinding efficiency.

A further object of the invention is the provision of an edging machine of the above character having means for maintaining the glass sheets or plates in proper vertical position as they are carried forwardly beneath the grinding wheel and for firmly holding them in such a manner that vibration of the said sheets or plates and any breakage incident thereto is reduced to a minimum.

A still further object of the invention is the provision of an edging machine of the above character which is of relatively simple inexpensive construction, easy to assemble and adjust, positive and rapid in action, efficient and durable in service, and a general improvement in the art.

Other objects and advantages of the invention

will become more apparent during the course of the following description, when taken in connection with the accompanying drawings.

In the drawings, wherein like numerals are employed to designate like parts throughout the same:

Fig. 1 is a side elevation of an edging machine constructed in accordance with the invention;

Fig. 2 is a horizontal longitudinal section taken substantially on line 2—2 of Fig. 1;

Fig. 3 is a plan view of the grinding wheel and one of the hold-down units for the glass sheets or plates being ground;

Fig. 4 shows an alternate type of grinding wheel;

Fig. 5 is a detail section taken substantially on line 5—5 of Fig. 1;

Fig. 6 is an elevation of one of the dash-pots used in the machine, partially broken away; and

Fig. 7 is a diagrammatic view illustrating the operation of the machine.

With reference now to the drawings, the machine comprises in general the means A for supporting the glass sheets 10 to be ground on edge in a vertical position and which sheets are adapted to be passed along said supporting means beneath the grinding mechanism B including a rotatable grinding wheel 11.

The means A for supporting the glass sheets 10 comprises a substantially horizontal runway including the spaced parallel longitudinally extending side boards 12 and 13 carrying therebetween a series of horizontally aligned freely rotatable conveyor rolls 14 leading to the grinding wheel 11 and a series of similar conveyor rolls 15 leading away from said wheel. The conveyor rolls 14 and 15 are adapted to support the glass sheets to be ground on edge in a vertical position and are preferably provided with grooves 16 for receiving the lower edges of the said sheets therein. The conveyor rolls 14 serve to convey the glass sheets to the grinding wheel 11, while the conveyor rolls 15 receive the sheets as they pass from said wheel and convey them either to a second grinding wheel, a polishing wheel or any suitable point.

The glass sheets 10 are adapted to be moved continuously forwardly along the supporting runway and beneath the grinding wheel 11. Any suitable means may be provided for propelling the glass sheets forwardly, and the means herein shown by way of example comprises a pusher block 17 engaging the rear edges of the glass sheets. This pusher block is carried by a sprocket chain 18 which slides along upon the upper

edge of one of the side boards 12 or 13 of the sheet supporting runway.

The grinding wheel 11 is mounted upon a horizontal shaft 19 journaled at its opposite ends in bearings 20 and 21 which are carried at one end of a relatively long, substantially horizontal supporting arm 22. The supporting arm 22 is pivotally mounted adjacent its opposite end upon a horizontal shaft 23 supported at its opposite ends in bearings 24 and 25 carried by vertical channel beams 26 and 27 respectively. Each bearing 24 and 25 is carried by a bracket 28 having a base flange 29 secured to the respective channel beam 26 or 27 by bolts or the like 30.

The supporting arm 22 is provided with spaced bearing blocks 31 and 32 through which the shaft 23 extends and upon which said supporting arm is rockably mounted. Carried upon the shaft 23 between the bearing blocks 31 and 32 is a collar 33 secured to said shaft by a screw or the like 34. The provision of the collar 33 prevents the supporting arm 22 from shifting laterally upon the shaft 23. The fastening bolts 30 for brackets 28 pass through vertical slots in the base flanges 29 so that the said brackets can be adjusted vertically to raise or lower the supporting arm 22 and grinding wheel 11. To effect this adjustment of the brackets 28, there is secured to each channel beam 26 and 27 an angle plate 35 (Fig. 1) through which is threaded a vertical screw 36 having its upper end engaging the respective bearing 24 or 25. By first loosening the bolts 30 and then adjusting screws 36, the brackets 28 can be moved vertically to raise or lower the supporting arm and grinding wheel.

Mounted upon the supporting arm 22 at the end thereof remote from the grinding wheel 11, is a motor 37 for driving the said wheel. The driving of the grinding wheel is effected by means of an endless belt 38 trained about a pulley 39 keyed to the shaft of motor 37 and also about a pulley 40 fixed to one end of the grinding wheel shaft 19. The drive belt 38 and pulleys 39 and 40 may be enclosed in a housing 41 if desired.

The grinding wheel 11 may be provided with a plain or flat grinding surface, as shown in Fig. 3, or it may be provided with a plurality of peripheral grooves 42 as illustrated in Fig. 4 for receiving the curved upper edges *a* of the glass sheets 10 therein to effect a rounding of said edges.

In the operation of the machine, the glass sheets 10 are initially supported on edge upon the conveyor rolls 14 and moved forwardly thereover to and beneath the grinding wheel 11. When in normal inoperative position, the grinding wheel assumes the position shown in Fig. 1 where it is disposed in the path of travel of the glass sheets 10. As the forward edges of the glass sheets engage the grinding wheel, they act to move the said wheel upwardly by rocking the supporting arm 22 upon shaft 23. However, since the grinding wheel is mounted for free vertical floating movement and normally urged downwardly by its own weight into engagement with the sheets 10 it is free to follow the upper edges *a* of the said sheets regardless of the curvature thereof.

The present invention also contemplates the provision of novel means for effectively maintaining the glass sheets 10 in proper vertical position and against vibration during the grinding operation whereby to facilitate an even uniform grinding of the sheet edges as well as reducing the liability of breakage of the glass to a mini-

5 mum. Such means comprises a plurality of hold-down units 43, 44, and 45 mounted beneath the path of travel of the glass sheets and so spaced from one another that the sheets are engaged by at least two of the units during the grinding thereof.

Each of the hold-down units 43, 44, and 45 comprises a pair of inclined arms 46 and 47 disposed at opposite sides of the sheet supporting runway and pivoted at their lower ends upon horizontal trunnions 48 and 49 formed upon brackets 50 and 51 carried by the side boards 12 and 13 respectively of said runway. The inclined arms 46 and 47 are connected together at their upper ends by a horizontal substantially U-shaped strap 52 carrying a hold-down roller 53 adapted to engage the upper edges of the glass sheets. The roller 53 is preferably provided with grooves 54 for receiving the upper edges of the glass sheets therein. Also mounted upon the horizontal trunnions 48 and 49 outwardly of and secured to the inclined arms 46 and 47 are the depending legs 55 and 56 respectively having cylindrical end portions 57 and 58 upon which are slidably mounted the weights 59 and 60. The depending legs 55 and 56 extend at substantially right angles to the inclined arms 46 and 47 and cooperate therewith to form bell-crank levers which are normally urged in a clockwise direction 20 upon the trunnions 48 and 49 by the weights 59 and 60 so as to force the roller 53 downwardly into engagement with the upper edges of the glass sheets. By proper adjustment of the weights 59 and 60, the pressure of the roller 53 upon the sheet edges can be varied as desired.

40 To assist in maintaining the hold-down rollers 53 in firm engagement with the upper edges of the glass sheets as the said sheets pass therebeneath, there is associated with each hold-down unit 43, 44, and 45 a dash-pot 61 which may be of the construction illustrated in Fig. 6. The dash-pot 61 comprises an elongated cylindrical casing closed at its opposite ends and pivoted at its lower end as at 62 to a fixed bracket 63 (Fig. 1). Slidably mounted within the casing is a piston rod 64 carrying at its lower end a piston 65 which snugly engages the wall of said casing. The piston 65 is provided with a plurality of openings 66 extending vertically therethrough and secured upon the upper surface of the piston is a flexible disk 67.

45 When the piston 65 is moved upwardly within the casing, the flexible disk 67 will assume the position shown in full lines in Fig. 6 and thus act to close the openings 66. Consequently, upon upward movement of the piston 65 the liquid contained within the casing above said piston cannot pass through the openings 66 and is therefore by-passed around the piston into the lower end of the casing through the pipes 68, 69, and 70. On the other hand, when the piston 65 moves downwardly, the marginal edge portion of the flexible disk 67 will be forced upwardly into broken line position so that the liquid beneath the piston can flow through the openings 66. A valve 71 is preferably interposed in the pipe 69 to control the flow of the liquid therethrough. The piston rod 64 extends through the upper end of the casing and is internally threaded to receive therein one end of a threaded rod 72 (Fig. 1) which is in turn threaded at its upper end in a block 73 pivoted as at 74 to one of the inclined arms 46 or 47 intermediate the ends thereof.

50 When the glass sheets 10 are moved forwardly along the supporting runway, the rollers 53 of

the hold-down units 43, 44, and 45 are successively engaged by the upper edges *a* of the sheets, and as the said sheets pass beneath each roller, the said roller is moved upwardly thereby due to the swinging of the arms 46 and 47 upon trunnions 48 and 49. The weights 58 and 60 will of course serve to hold the roller 53 down in engagement with the sheet edges. Upon upward movement of the roller 53, the respective piston rod 64 will also be drawn upwardly to effect upward movement of the piston 65. This will result in the flexible disk 67 being flattened out, as shown in full lines in Fig. 6, to close the openings 66 and thus prevent the liquid from passing through said openings from the upper end of the casing into the lower end thereof. Since the liquid cannot pass through the openings 66 it will flow through pipes 68, 69, and 70 into the lower end of the casing. By proper regulation of the valve 71, the flow of liquid through the pipe 69 can be so controlled that it will offer a predetermined resistance to the upward movement of the roller 53 whereby said roller will exert a firm, steady downward pressure upon the upper edges of the glass sheets to hold them in proper vertical position, as well as minimize vibration thereof during grinding. On the other hand, when the glass sheets pass beyond the roller 53, the roller is permitted to drop quite rapidly to normal inoperative position. This is due to the fact that, as the roller moves downwardly to also effect downward movement of the piston 65, the disk 67 will assume the broken line position in Fig. 6, so that the liquid can pass upwardly through the openings 66. Although it is preferred to make use of a dash-pot arrangement as above described, other means may be employed to retard the upward movement of the roller 53, such as a check valve or the like.

As the glass sheets 10 move forwardly along the supporting runway, they will engage the grinding wheel 11 and, due to its pivotal mounting, the said wheel will be moved upwardly by the sheets and caused to follow the contour of the upper edges thereof as the sheets pass beneath said wheel. After the sheets pass beyond the grinding wheel, it is adapted to drop downwardly by its own weight to normal inoperative position. For the purpose of retarding the downward movement of the grinding wheel to prevent it from dropping too rapidly, there is provided a dash-pot 75 similar to the dash-pots 61 of the hold-down units 43, 44, and 45.

The dash-pot 75 is pivoted at its lower end to the supporting arm 22 as at 76, while the piston rod 77 thereof has threaded in its outer end a rod 78 carried by a block 79. The block 79 has secured thereto a horizontal pin 80 which is loosely received within a vertical slot 81 and in a fixed plate 82. The dash-pot 75 is preferably of the same construction as the dash-pot 61 above described, with the exception that the flexible disk 67 thereof is secured to the bottom of the piston 65 rather than to the top thereof as shown in Fig. 6. This arrangement will not retard the upward movement of the grinding wheel but will serve to prevent a too sudden dropping of the wheel after the glass sheets pass therebeyond. That is to say, the liquid within the dash-pot will be permitted to flow through the openings 66 in the piston 65 upon upward movement of the grinding wheel whereas when the said wheel moves downwardly the openings will be closed by the flexible disk 67 and the liquid by passed through the pipes 68, 69, and 70.

In order to obtain an even and uniform grinding of the upper curved edges *a* of the glass sheets, it is necessary that the pressure exerted by the grinding wheel upon the sheet edges be varied as the sheets pass beneath said wheel. Referring particularly to Fig. 7, as the glass sheets 10 pass beneath grinding wheel 11 and the said wheel travels along the curved edges *a* from point *b* to point *c*, the only pressure required to be exerted upon the sheets is the weight of the grinding wheel and its associated parts. However, as the grinding wheel passes from point *c* to point *d*, it is necessary that the pressure exerted thereby upon the sheet edges be increased, while from point *d* to point *e* the pressure can again be decreased to the weight of the grinding wheel and its associated parts. In other words, as the curve of the sheet edges flattens out, such as from point *a* to point *d*, it is necessary that the grinding pressure be increased. Although it is to be expressly understood that the invention is not limited to the use of any specific pressures (as this depends upon the curvature of the sheet edges), it has been found that, when grinding glass sheets having their upper edges curved in the manner illustrated in Fig. 7, it is preferred that the grinding wheel exert approximately twenty-five pounds pressure upon the sheets as said wheel passes from point *b* to point *c*, approximately sixty to seventy pounds pressure in passing from point *c* to point *d*, and approximately twenty-five pounds pressure from point *d* to point *e*.

In accordance with the invention, the pressure exerted by the grinding wheel 11 upon the upper edges of the glass sheets is adapted to be automatically varied as the sheets pass therebeneath in the following manner. Secured to the supporting arm 22 is a bracket 83 having a relatively long slot 84 therein. Slidably received within the slot 84 is a horizontal pin 85 carried at the lower end of a substantially vertical bar 86, the upper end of which is operatively associated with an electromagnetic holding unit designated in its entirety by the numeral 87. Secured to the bar 86, adjacent the lower end thereof, is a substantially horizontal platform 88, while suspended above the platform is a weight 89. This weight consists preferably of a disk carried at the lower ends of cables 90 and having an open slot 91 therein for receiving the bar 86. As the grinding wheel 11 is forced upwardly by the glass sheets moving therebeneath, the supporting arm 22 will be rocked upon shaft 23 in a clockwise direction to also move the bar 86 upwardly. Upon upward movement of said bar, the platform 88 will engage and lift the disk 89 and, obviously, when the disk 89 is supported upon the platform 88 the pressure exerted by the grinding wheel 11 upon the sheet edges will be increased according to the weight of said disk.

In practice, the disk 89 is adapted to be lifted by the platform 88 when the grinding wheel 11 reaches the point *c* as shown in full lines in Fig. 7, so that during the travel of the wheel from point *c* to point *d* the added weight of the disk 89 will be applied to the edges of the glass sheets. On the other hand, when the grinding wheel reaches point *d* and begins to move downwardly to point *e* the pressure is adapted to be again decreased as described above. This is accomplished by permitting the grinding wheel 11 to move downwardly by its own weight while at the same time maintaining the bar 86 and disk 89 in elevated position by operation of the holding unit 87.

This unit comprises a horizontal, substantially U-shaped bracket 92 arranged between a pair of spaced vertical hangers 93 and 94 and provided with trunnions 95 and 96 which are received within openings in said hangers 93 and 94 respectively. Carried by the bracket 92 is a solenoid 97 having a plunger 98 to which is pivoted as at 99 one end of a bolt 100 upon which is threaded a nut 101. The bracket 92 is provided with a head 102 formed with a rectangular groove or recess 103 in which the bar 86 is slidably received. The head 102 of bracket 92 is also provided with spaced ears 104 and 105 (Fig. 1) between which is received a clamping block 106 pivoted to said ears at one end as at 107 and having an open slot 108 in its opposite end for receiving the bolt 100. The clamping block 106 is further provided at one side with a notch 109 and disposed in said notch is a pin 110 upon which is pivoted a clamping plate 111 having a vertically disposed flange 112 extending parallel with bar 86 and having its outer face covered with a strip of rubber, rubber composition or the like 113. Upon energization of the solenoid 97, the plunger 98 thereof is adapted to be drawn inwardly to swing the clamping block 106 upon its pivot 107 to cause the bar 86 to be firmly clamped against movement within the recess 103 by means of the flange 112 on clamping plate 111. Upon deenergization of the solenoid, however, the clamping block 106 is forced outwardly by a spring 114 to release the clamping action upon the bar 86.

During the grinding operation, and as the grinding wheel 11 passes along the sheet edges from point *b* to point *d*, the solenoid 97 is adapted to be deenergized so that the bar 86 can move upwardly within the recess 103 upon raising of the grinding wheel. However, when the grinding wheel reaches point *d*, and begins its downward movement, the solenoid is adapted to be automatically energized to maintain the bar 86 and disk 89 in elevated position, while permitting the grinding wheel to move downwardly by its own weight. To this end, a limit switch 115 is secured to the sheet supporting runway and connected in series with the solenoid, said switch having a pivoted lever arm 116 carrying at its outer end a roller 117. When the glass sheets move beneath the grinding wheel and the said wheel reaches the point *d* on the sheet edges, the pusher block 117 for the sheets is adapted to engage roller 117 and force lever arm 116 downwardly to close the switch 115. The closing of the switch will effect the energizing of the solenoid 97 and the clamping of the bar 86 in raised position. Due to the relatively long slot 84 in bracket 83, the grinding wheel can then move downwardly as it passes from point *d* to point *e* while the weight 89 is held in raised position along with the bar 86. When the pusher block 117 passes beyond limit switch 115, the switch will be automatically opened to deenergize the solenoid and thereby release the bar and weight so that they can move downwardly to initial position. By the time the switch is opened, the glass sheets will have passed beyond the grinding wheel.

It will of course be appreciated that one or any desired number of grinding wheels 11 may be employed and also that one or a plurality of polishing wheels can be arranged in line therewith, if preferred. Further, the machine may be used for the edging of sheets or plates of other material and is not restricted to use in the surfacing of glass sheets.

It is to be understood that the form of the in-

vention herewith shown and described is to be taken as the preferred embodiment of the same, and that various changes in the shape, size and arrangement of parts may be resorted to without departing from the spirit of the invention or the scope of the subjoined claims.

We claim:

1. In apparatus for grinding the edges of sheets or plates of glass and the like, means for supporting the sheet on edge in a vertical position and for carrying the same forwardly in a generally horizontal direction, means mounted above the path of travel of the sheet for grinding the upper edge of said sheet during forward movement thereof, means for mounting said grinding means for free vertical movement so that it can freely follow the contour of the upper edge of the sheet, the weight of the grinding means exerting an initial pressure upon the upper edge of the sheet, and separate pressure means normally ineffective and rendered effective by upward movement of the grinding means for applying increased pressure to said grinding means to urge it downwardly into engagement with the upper edge of said sheet.
2. In apparatus for grinding the edges of sheets or plates of glass and the like, means for supporting the sheet on edge in a vertical position and for carrying the same forwardly in a generally horizontal direction, means mounted above the path of travel of the sheet for grinding the upper edge of said sheet during forward movement thereof, means for mounting said grinding means for free vertical movement so that it can freely follow the contour of the upper edge of the sheet, and a weight adapted to be automatically applied to the grinding means upon upward movement thereof to urge said grinding means downwardly with increased pressure into engagement with the upper edge of said sheet.
3. In apparatus for grinding the edges of sheets or plates of glass and the like, means for supporting the sheet on edge in a vertical position and for carrying the same forwardly in a generally horizontal direction, a grinding wheel beneath which the sheet is adapted to be moved, a supporting arm carrying said grinding wheel at one end and pivotally mounted adjacent its opposite end, a motor carried by said supporting arm for driving said grinding wheel, said grinding wheel being adapted to freely follow the contour of the upper edge of the sheet as said sheet moves therebeneath, and pressure means independent of said supporting arm mounted in spaced relation thereabove and adapted to be engaged by the said supporting arm upon upward movement thereof to urge said grinding wheel downwardly with increased pressure into engagement with the upper edge of said sheet.
4. In apparatus for grinding the edges of sheets or plates of glass and the like, means for supporting the sheet on edge in a vertical position and for carrying the same forwardly in a generally horizontal direction, a grinding wheel beneath which the sheet is adapted to be moved, a supporting arm carrying said grinding wheel at one end and pivotally mounted adjacent its opposite end, a motor carried by said supporting arm for driving said grinding wheel, said grinding wheel being adapted to freely follow the contour of the upper edge of the sheet as said sheet moves therebeneath, the weight of the grinding wheel and associated parts exerting an initial pressure upon the upper edge of the sheet, sepa-

rate pressure means independent of said supporting arm mounted in spaced relation thereabove and adapted to be engaged by the said supporting arm upon upward movement thereof to urge said grinding wheel downwardly with increased pressure into engagement with the upper edge of said sheet.

5. In apparatus for grinding the edges of sheets or plates of glass and the like, means for supporting the sheet on edge in a vertical position and for carrying the same forwardly in a generally horizontal direction, a grinding wheel beneath which the sheet is adapted to be moved, a supporting arm carrying said grinding wheel at one end and pivotally mounted adjacent its opposite end, a motor carried by said supporting arm for driving said grinding wheel, said grinding wheel being adapted to freely follow the contour of the upper edge of the sheet as said sheet moves therebeneath, and a weight adapted to be picked up by said supporting arm upon upward movement of the grinding wheel to urge said grinding wheel downwardly with increased pressure into engagement with the upper edge of said sheet.

6. In apparatus for grinding the edges of sheets or plates of glass and the like, means for supporting the sheet on edge in a vertical position and for carrying the same forwardly in a generally horizontal direction, a grinding wheel beneath which the sheet is adapted to be moved, a supporting arm carrying said grinding wheel at one end and pivotally mounted adjacent its opposite end, a motor carried by said supporting arm for driving said grinding wheel, said grinding wheel being adapted to freely follow the contour of the upper edge of the sheet as said sheet moves therebeneath, a weight adapted to be picked up by said supporting arm upon upward movement of the grinding wheel to urge said grinding wheel downwardly with increased pressure into engagement with the upper edge of said sheet, and means actuated when the sheet reaches a predetermined position beneath the grinding wheel for holding said weight in elevated position while said grinding wheel moves downwardly as said sheet passes therebeyond.

7. In apparatus for grinding the edges of sheets or plates of glass and the like, means for supporting the sheet on edge in a vertical position and for carrying the same forwardly in a generally horizontal direction, a grinding wheel beneath which the sheet is adapted to be moved, a supporting arm carrying said grinding wheel at one end and pivotally mounted adjacent its opposite end, a motor carried by said supporting arm for driving said grinding wheel, said grinding wheel being adapted to freely follow the contour of the upper edge of the sheet as said sheet moves therebeneath, a weight adapted to be picked up by said supporting arm upon upward movement of the grinding wheel to urge said grinding wheel downwardly with increased pressure into engagement with the upper edge of said sheet, means actuated when the sheet reaches a predetermined position beneath the grinding wheel for holding said weight in elevated position while said grinding wheel moves downwardly as said sheet passes therebeyond, and means for retarding the downward movement of the said grinding wheel.

8. In apparatus for grinding the edges of sheets or plates of glass and the like, means for supporting the sheet on edge in a vertical position

5 and for carrying the same forwardly in a generally horizontal direction, a grinding wheel beneath which the sheet is adapted to be moved, a supporting arm carrying said grinding wheel at one end and pivotally mounted adjacent its opposite end, a motor carried by said supporting arm for driving said grinding wheel, said grinding wheel being adapted to freely follow the contour of the upper edge of the sheet as said sheet moves therebeneath, a weight adapted to be picked up by said supporting arm upon upward movement of the grinding wheel to urge said grinding wheel downwardly with increased pressure into engagement with the upper edge of said sheet, means for propelling the sheet forwardly beneath the grinding wheel, and means actuated by said propelling means when the sheet reaches a predetermined position beneath said grinding wheel for holding said weight in elevated position while said grinding wheel moves downwardly as said sheet passes therebeyond.

9. In apparatus for grinding the edges of sheets or plates of glass and the like, means for supporting the sheet on edge in a vertical position and for carrying the same forwardly in a generally horizontal direction, a grinding wheel beneath which the sheet is adapted to be moved, a supporting arm carrying said grinding wheel at one end and pivotally mounted adjacent its opposite end, a motor carried by said supporting arm for driving said grinding wheel, said grinding wheel being adapted to freely follow the contour of the upper edge of the sheet as said sheet moves therebeneath, a weight adapted to be picked up by said supporting arm upon upward movement of the grinding wheel to urge said grinding wheel downwardly with increased pressure into engagement with the upper edge of said sheet, means for propelling the sheet forwardly beneath the grinding wheel, means actuated by said propelling means when the sheet reaches a predetermined position beneath said grinding wheel for holding said weight in elevated position while said grinding wheel moves downwardly as said sheet passes therebeyond, and means for retarding the downward movement of the said grinding wheel.

10. In apparatus for grinding the edges of sheets or plates of glass and the like, means for supporting the sheet on edge in a vertical position and for carrying the same forwardly in a generally horizontal direction, a grinding wheel beneath which the sheet is adapted to be moved, a supporting arm carrying said grinding wheel at one end and pivotally mounted adjacent its opposite end, a motor carried by said supporting arm for driving said grinding wheel, said grinding wheel being adapted to freely follow the contour of the upper edge of the sheet as said sheet moves therebeneath, a weight suspended above the supporting arm, a substantially vertical bar pivotally connected at its lower end to said supporting arm and having means for picking up said weight upon upward movement of the grinding wheel to urge said grinding wheel downwardly with increased pressure into engagement with the upper edge of the sheet, and means for holding said bar and weight in elevated position while said grinding wheel moves downwardly as said sheet passes therebeyond.

11. In apparatus for grinding the edges of sheets or plates of glass and the like, means for supporting the sheet on edge in a vertical position and for carrying the same forwardly in a generally horizontal direction, a grinding wheel be-

neath which the sheet is adapted to be moved, a supporting arm carrying said grinding wheel at one end and pivotally mounted adjacent its opposite end, a motor carried by said supporting arm for driving said grinding wheel, said grinding wheel being adapted to freely follow the contour of the upper edge of the sheet as said sheet moves therebeneath, a weight suspended above the supporting arm, a substantially vertical bar pivotally connected at its lower end to said supporting arm and having means for picking up said weight upon upward movement of the grinding wheel to urge said grinding wheel downwardly with increased pressure into engagement with the upper edge of the sheet, and electromagnetic means operable when the sheet reaches a predetermined position beneath said grinding wheel to hold said bar and weight in elevated position while said grinding wheel moves downwardly as said sheet passes therebeyond.

12. In apparatus for grinding the edges of sheets or plates of glass and the like, means for supporting the sheet on edge in a vertical position and for carrying the same forwardly in a generally horizontal direction, a grinding wheel beneath which the sheet is adapted to be moved, a supporting arm carrying said grinding wheel at one end and pivotally mounted adjacent its opposite end, a motor carried by said supporting arm for driving said grinding wheel, said grinding wheel being adapted to freely follow the contour of the upper edge of the sheet as said sheet moves therebeneath, a weight suspended above the supporting arm, a substantially vertical bar pivotally connected at its lower end to said supporting arm and having means for picking up said weight upon upward movement of the grinding wheel to urge said grinding wheel downwardly with increased pressure into engagement with the upper edge of the sheet, electromagnetic means operable when the sheet reaches a predetermined position beneath said grinding wheel to hold said bar and weight in elevated position while said grinding wheel moves downwardly as said sheet passes therebeyond, and means for automatically rendering said electromagnetic means inoperative when the sheet passes beyond said grinding wheel to cause the lowering of the said bar and weight.

13. In apparatus for grinding the edges of sheets or plates of glass and the like, means for supporting the sheet on edge in a vertical position and for carrying the same forwardly in a generally horizontal direction, a grinding wheel beneath which the sheet is adapted to be moved, a supporting arm carrying said grinding wheel at one end and pivotally mounted adjacent its opposite end, a motor carried by said supporting arm for driving said grinding wheel, said grinding wheel being adapted to freely follow the contour of the upper edge of the sheet as said sheet moves therebeneath, a weight suspended above the supporting arm, a substantially vertical bar pivotally connected at its lower end to said supporting arm and having means for picking up said weight upon upward movement of the grinding wheel to urge said grinding wheel downwardly with increased pressure into engagement with the upper edge of the sheet, means for propelling the sheet forwardly beneath the grinding wheel, electromagnetic means associated with said bar, and means operable by said propelling means when the sheet reaches a predetermined position beneath said grinding wheel for energizing said electromagnetic means

to hold said bar and weight in elevated position while the said grinding wheel moves downwardly as said sheet passes therebeyond.

14. In apparatus for grinding the edges of sheets or plates of glass and the like, means for supporting the sheet on edge in a vertical position and for carrying the same forwardly in a generally horizontal direction, a grinding wheel beneath which the sheet is adapted to be moved, 10 a supporting arm carrying said grinding wheel at one end and pivotally mounted adjacent its opposite end, a motor carried by said supporting arm for driving said grinding wheel, said grinding wheel being adapted to freely follow the contour of the upper edge of the sheet as said sheet moves therebeneath, a weight suspended above the supporting arm, a substantially vertical bar pivotally connected at its lower end to said supporting arm and having means for picking up 20 said weight upon upward movement of the grinding wheel to urge said grinding wheel downwardly with increased pressure into engagement with the upper edge of the sheet, means for propelling the sheet forwardly beneath the grinding wheel, electromagnetic means associated with said bar, a limit switch adapted to be closed by said propelling means when the sheet reaches a predetermined position beneath said grinding wheel for energizing said electromagnetic means to hold said bar and weight in elevated position while said grinding wheel moves downwardly as said sheet passes therebeyond, said limit switch being automatically opened as said propelling means passes out of 30 engagement therewith to deenergize said electromagnetic means and cause the lowering of the said bar and weight.

15. In apparatus for grinding the edges of sheets or plates of glass and the like, means for supporting the sheet on edge in a vertical position and for carrying the same forwardly in a generally horizontal direction, means for holding the sheet in proper vertical position during grinding comprising a pair of inclined arms arranged at opposite sides of the path of travel of the sheet and pivotally mounted at their lower ends beneath the path of travel of said sheet, a hold-down roller carried between said arms at their upper ends and engaging the upper edge of the sheet, and means for urging said arms about their pivots to hold said roller down in engagement with the sheet edge.

16. In apparatus for grinding the edges of sheets or plates of glass and the like, means for supporting the sheet on edge in a vertical position and for carrying the same forwardly in a generally horizontal direction, means for holding the sheet in proper vertical position during grinding comprising a pair of inclined arms arranged at opposite sides of the path of travel of the sheet and pivotally mounted at their lower ends beneath the path of travel of said sheet, a hold-down roller carried between said arms at their upper ends and engaging the upper edge of the sheet, means for urging said arms about their pivots to hold said roller down in engagement with the sheet edge, and means for retarding the upward movement of the said roller during travel of the sheet therebeneath to hold it in firm engagement with the edge of said sheet.

17. In apparatus for grinding the edges of sheets or plates of glass and the like, means for supporting the sheet on edge in a vertical position and for carrying the same forwardly in a general-

ly horizontal direction, means for holding the sheet in proper vertical position during grinding comprising a pair of inclined arms arranged at opposite sides of the path of travel of the sheet and pivotally mounted at their lower ends beneath the path of travel of said sheet, a hold-down roller carried between said arms at their upper ends and engaging the upper edge of the sheet, a pair of legs secured to the lower ends of said arms and extending at substantially right angles thereto, and weights carried by said legs for rocking the said arms about their pivots to hold said roller down in engagement with the sheet edge.

18. In apparatus for grinding the edges of sheets or plates of glass and the like, means for supporting the sheet on edge in a vertical position and for carrying the same forwardly in a generally horizontal direction, means for holding the sheet in proper vertical position during grinding comprising a pair of inclined arms arranged at opposite sides of the path of travel of the sheet and pivotally mounted at their lower ends beneath the path of travel of said sheet, a hold-down roller carried between said arms at their upper ends and engaging the upper edge of the sheet, a pair of legs secured to the lower ends of said arms and extending at substantially right angles thereto, weights carried by said legs for rocking the said arms about their pivots to hold said roller down in engagement with the sheet edge, and means connected to the said arms for retarding the upward movement of the said roller during travel of the sheet therebeneath to hold it in firm engagement with the edge of the sheet.

19. In apparatus for grinding the edges of sheets or plates of glass and the like, means for

supporting the sheet on edge in a vertical position and for carrying the same forwardly in a generally horizontal direction, means mounted above the path of travel of the sheet for grinding the upper edge of said sheet during the forward movement thereof, means for mounting said grinding means for free vertical movement so that it can freely follow the contour of the upper edge of the sheet, and separate pressure means independent of said grinding means mounted in spaced relation thereabove, said separate pressure means being normally ineffective and rendered effective by upward movement of said grinding means to urge the said grinding means downwardly with increased pressure into engagement with the upper edge of said sheet.

20. In apparatus for grinding the edges of sheets or plates of glass and the like, means for supporting the sheet on edge in a vertical position and for carrying the same forwardly in a generally horizontal direction, a grinding wheel beneath which the sheet is adapted to be moved, a supporting arm carrying said grinding wheel at one end and pivotally mounted adjacent its opposite end, a motor carried by said supporting arm for driving said grinding wheel, said grinding wheel being adapted to freely follow the contour of the upper edge of the sheet as said sheet moves therebeneath, and separate pressure means mounted in spaced relation above the grinding wheel adapted to be picked up by said supporting arm upon upward movement of said grinding wheel to urge the said grinding wheel downwardly with increased pressure into engagement with the upper edge of said sheet.
